WILLIAM L. McDOWELL, OF PHILADELPHIA, PENNSYLVANIA.

Design No. 2,716, dated August 6, 1867.

DESIGN FOR A STOVE-TOP.

The Schedule referred to in these Letters Patent and making part of the same.

TO ALL WHOM IT MAY CONCERN:

Be it known that I, WILLIAM L. McDOWELL, of the city of Philadelphia, in the State of Pennsylvania, have invented or produced a new and original Design for a Stove-Top; and I do hereby declare that the following is a full, clear, and exact description, reference being had to the accompanying drawing, making a part of this specification.

This design consists of an ornamented bowl, A, and perforated ornamented lid B, as represented in the drawing. The lower part of the bowl A has nearly vertical sides, a' , and a flat bottom, a'' . From the top of the vertical sides a' the bowl is curved outward and ornamented, as shown, with raised figures a''' . The lid B is formed of three series of perforated elevations $b' b'' b'''$, surmounted by a handle, b'''' , and rests upon the upper edge of the bowl A, as shown; the whole, together, forming an ornamental top for a stove for evaporating water.

What I claim as my invention, and desire to secure by Letters Patent, is—

The design for a stove-top herein set forth and shown.

WM. L. McDOWELL.
